US00D667064S

(12) **United States Design Patent**
Guyer et al.

(10) **Patent No.:** **US D667,064 S**
(b4) **Date of Patent:** **** Sep. 11, 2012**

(54) **LAWN GAME COMPONENT**

(76) Inventors: **Reynolds W. Guyer**, Boca Grande, FL (US); **Kathryn D. Guyer**, Saint Paul, MN (US)

(**) Term: **14 Years**

(21) Appl. No.: **29/402,531**

(22) Filed: **Sep. 23, 2011**

Related U.S. Application Data

(62) Division of application No. 29/344,699, filed on Oct. 2, 2009, now Pat. No. Des. 648,404.
